UNITED STATES PATENT OFFICE.

BRIAN T. MORAN, OF NEW YORK, N. Y.

SAVINGS BANK.

Application filed April 12, 1926. Serial No. 101,467.

This invention appertains to pocket saving banks of the type shown in my pending application filed November 11, 1925, Serial No. 68,419.

5 The primary object of the present invention is to provide novel means for locking the coin tray and the closure cap connected therewith in the body of the bank against accidental and unauthorized movement, the means 10 being of an exceptionally simple character and entirely eliminating the provision of complicated locking latches and the like.

Another object of the invention is to provide a pocket coin bank having a tray slidably associated with the body thereof, one 15 end of the tray having permanently attached thereto a cap for closing one end of the body and coin guards carried by the opposite end of the tray for overlying entrance slots 20 formed in the cap permanently secured to the body, the coin guards acting as means for stripping the coins from the body of the bank when the cap and tray is removed therefrom, the coin guards being so arranged as to also 25 act as means for detachably locking the tray in the body against unauthorized removal.

A further object of the invention is the provision of a resilient coin guard and stripper carried by the removal tray of the bank having 30 offset corners formed thereon acting as locking dogs for engaging in suitable keeper recesses formed in the body of the bank, when the tray is associated with the body.

A further object of the invention is the provision of a novel implement insertable 35 through the coin entrance slots for moving the offset corners out of the keeper recesses, whereby the tray and the removable cap connected therewith can be slid from out of the body of the bank.

A further object of the invention is to provide novel means for limiting the inserting movement of the release device into the coin receiving slots.

45 With these and other objects in view, the invention consists in the novel construction, arrangement and formation of parts, as will be hereinafter more specifically described, claimed, and illustrated in the accompanying 50 drawings, in which drawings:

Figure 1 is a side elevation of the improved bank showing parts thereof broken away and in section to illustrate the combined coin guard, stripper and lock.

55 Figure 2 is an end elevation of the bank

showing the terminal through which the coins are inserted and the lock releasing device,

Figure 3 is an elevation of the removable tray of the bank showing the novel coin guard carried thereby,

60 Figure 4 is a side elevation of the body portion of the bank with the tray removed therefrom, a portion of the body being shown broken away and in section to illustrate the keeper recesses formed in the side walls of the bank for receiving the locking ears 65 formed on the corners of the coin guards,

Figure 5 is a transverse section through the removable tray taken on the line 5—5 of Figure 3 looking in the direction of the arrows,

70 Figure 6 is a transverse section through the body portion of the bank taken on the line 6—6 of Figure 1 looking in the direction of the arrows,

75 Figure 7 is a fragmentary longitudinal section through the bank on an enlarged scale taken on the line 7—7 of Figure 1 looking in the direction of the arrows, showing the tray in its locked position within the body of the bank,

80 Figure 8 is a similar view showing the ears moved to their unlocked position by the release device, and

85 Figure 9 is a detail perspective view of the releasing device or key.

Referring to the drawings in detail, wherein similar reference characters designate corresponding parts throughout the several views, the letter A generally indicates the improved pocket coin savings bank which comprises the body 10 and the removable coin 90 tray or partition 25.

The body 10 can be constructed from sheet metal of the desired gage suitably treated to enhance the appearance thereof. The body 95 10 consists of the front and rear walls 11 and 12, and the side walls 13. The body 10 can be constructed in any desired way and as shown includes end pieces 14 and intermediate pieces 15 all of which are of a substantially U-shape in cross section as clearly shown in Figure 6. These pieces are placed together and secured in any desired way, such as by solder, welding or the like with the flanges 16 extending inwardly. As shown 100 the outer pieces 14 are provided with out-struck longitudinally extending legs 17 disposed in parallel relation to the flanges which receive guide retaining strips 18 which are adapted to be slid thereover. The front and 110

rear walls can be provided with suitable means to permit a view to be had of the interior of the body and as shown these walls are provided with longitudinally extending sight slots 19. One end of the body is provided with a closure cap 20 which is fitted snugly over and rigidly secured to the said front and rear walls and side walls.

The coin tray 25 embodies a longitudinally extending plate 26 equal to the width of the body and adapted to be slidably mounted therein. One end of the plate 26 has secured thereto a cap 27 which is of substantially the same construction as the cap 20. It is obvious that when the tray 25 is inserted within the body 10 that the plate 26 will form a partition and the plate in connection with the ribs 16 define a plurality of longitudinally extending coin receiving channels 28. The cap 20 is provided, on each side of the longitudinal axis thereof, with rows of coin slots 21 so as to permit the insertion of the coins into the coin channelways 28. The front and rear walls 11 and 12 at the central channelways 28 and at a point slightly spaced from the coin slots 21 are provided with keeper recesses 22, for a purpose, which will be hereinafter more fully described. It is to be noted that the sides of the cap 20 overlie the recesses, so that the same can not be seen from the exterior of the bank.

The plate 26 of the coin tray 25 is also provided with longitudinally extending sight openings 29 which register with the sight slots 19 formed in the front and rear walls of the body 10 when the tray is in the body. The edges of the slots 19 are provided with resilient beads 23 for engaging the coins in the channelways 28 so as to normally prevent rattling of the coins but these beads can be dispensed with, if preferred, or other anti-rattling means substituted therefor.

The inner end of the plate 26 of the partition or coin tray 25 has permanently secured thereto, such as by solder or rivets 30 coin guards 31, 32 and 33, and these guards are provided for the coin entrance slots 21 so as to prevent removal of the coins therethrough and each of the guards is of a substantially V-shape in cross section and are placed so as to straddle the plate 26 and to permit the bight portions thereof to be permanently secured to the inner edge of the said plate. As stated the coin guards are of a substantially V-shape and each includes resilient legs 34 for normally engaging the front and rear walls of the body 10, whereby upon the introduction of the coins through one of the entrance slots 21, the legs 34 can be flexed and the coin will be permitted to readily slide into the desired channelways. However upon attempt to remove the coins, the same will engage under the legs, which will prevent movement of the coins through the slots. In accordance with this invention the free corners 65 of the legs 34 of the coin guards are bent lat-

erally to provide ears 35 which serve as means for engaging the coins so as to prevent the outward movement thereof through the coin slots. Particular attention is directed to the intermediate coin guard 32 and its ears 35, as the ears 35 also perform the function of locking dogs for engaging in the recesses 22 in the front and rear walls of the body 10, whereby unauthorized removal of the tray from the body will be prevented. Of course the guards 31 and 33 can also be utilized as locking means if desired, but it is preferred to only use the intermediate guard 32 in view of the fact that this guard is sufficient to form the locking means and also allow the quick release of the tray when the proper key is inserted through the intermediate entrance coin slots 21.

The guards 31, 32 and 33 in the present instance, also form means for stripping the coins from the channelways when the tray is unlocked and pulled from the body, the same as in the original application heretobefore mentioned.

In Fig. 9 of the drawings I have shown the preferred type of key utilized for unlocking the coin safe and in Figure 8 I have shown this key in use. This key comprises a substantially U-shaped body 40 formed of resilient material to include resilient legs 41 and 42. Each of the legs have struck from out of the same stop lugs 43 for limiting the inserting movement of the legs 41 and 42 within the central coin entrance slots 21. The inner edges of the legs can be provided with teeth 44, which can be dispensed with if preferred. When it is desired to unlock the tray it is merely necessary to insert the legs 41 and 42 of the key within the central coin slots 21 until the legs 34 of the intermediate coin guard 32 are flexed inward and the ears 35 are removed from the recesses 22. When the stop lugs 43 engage the outer face of the cap 20, it will be known that the lock has been released and that the tray can be pulled outward. In actual practice, it has been found that as the key is inserted through the coin slots the legs 34 of the intermediate coin guard 32 will be depressed and the key will start forcing the tray from out of the body and that the tray can then be removed by the bank official quickly.

From the foregoing description, it can be seen that I have provided a novel lock of an exceptionally simple and durable character for pocket savings bank which can be readily unlocked with a minimum amount of time and effort.

Changes in details may be made without departing from the spirit or the scope of this invention, but:

What I claim as new is:

1. A savings bank comprising a hollow body having coin entrance slots, a removable tray centrally within the body defining at

least a pair of coin slots, coin guards carried by the tray for said coin entrance slots, and means carried by a coin guard for engaging the body for releasably locking the tray in position in the body against unauthorized removal.

2. A savings bank comprising a hollow body, a removable tray disposed centrally within the body defining a pair of elongated coin compartments, one end of the body being provided with coin entrance slots, and means carried by the tray for preventing egress of coins through the slots and for engaging the coins in the compartments to strip the coins therefrom upon removal of the tray from the body and for locking the tray in the body against unauthorized removal.

3. A savings bank comprising a hollow body, a cap permanently secured to and closing one end of the body having coin entrance slots therein, a removable tray disposed centrally in the body defining at least a pair of coin compartments, a cap carried by the tray engaging and closing the end of the body remote from the first mentioned cap, and a single means carried by the inner end of the tray for preventing the egress of coins through the slots and for releasably locking the tray in the body against unauthorized removal.

4. A savings bank comprising a hollow body, a closure permanently connected to one end of the body, a tray slidably mounted centrally in the body defining at least a pair of elongated coin compartments having predetermined widths and thicknesses for receiving a particular size of coins, a closure carried by the outer end of the tray for engaging the end of the body remote from the first closure, the first mentioned closure having coin slots therein communicating with the coin compartments, a coin guard permanently secured to the inner end of the tray for preventing egress of coins through the slots, and means formed on one of the coin guards for engaging the body, for releasably locking the tray in the body against unauthorized removal.

5. A savings bank comprising a hollow body, a closure permanently connected to one end of the body, a tray slidably mounted centrally in the body defining at least a pair of elongated coin compartments, a closure carried by the outer end of the tray for engaging the end of the body remote from the first closure, certain walls of the body having keeper recesses formed therein covered by the first mentioned closure, and resilient coin guards carried by the inner end of the tray for preventing egress of coins through the coin receiving slots and for engaging in said recesses for releasably locking the tray in the body against unauthorized removal.

6. A savings bank comprising a hollow

body, a closure permanently connected to one end of the body, a tray slidably mounted centrally in the body defining at least a pair of elongated coin compartments, a closure carried by the outer end of the tray for engaging the end of the body remote from the first closure, the first mentioned closure having coin slots therein communicating with the coin compartments, a substantially V-shaped coin guard permanently secured to the inner end of the tray including resilient legs arranged on opposite sides of the tray lying within said compartments inward of the coin entrance slots for preventing egress of coins through the slots, certain walls of the body having keeper recesses formed therein in the path of the legs of the coin guard for receiving said legs when the tray is inserted within the body to its inner position for preventing unauthorized removal of the tray from the body, and means insertable through the coin slots for flexing said legs to permit the removal of the tray.

7. A savings bank comprising a hollow body, a closure permanently connected to one end of the body, a tray slidably mounted centrally in the body defining at least a pair of elongated coin compartments, a closure carried by the outer end of the tray for engaging the end of the body remote from the first closure, the first closure having coin entrance slots communicating with the channels, certain walls of the body having keeper recesses formed therein directly inward of the coin slots and normally closed by the first mentioned closure, a resilient coin guard of substantially V-shape permanently connected to the inner end of the tray for fitting within the coin channels including diverging resilient legs lying on opposite sides of the tray, laterally deflected ears formed on the free corners of the legs for snapping into and engaging the walls of the recesses when the tray is in its innermost position to prevent unauthorized removal of the tray from the body, and means insertable through the coin slots for flexing the legs to permit the removal of the tray from the body.

8. In a savings bank, a hollow body having coin entrance slots, a removable tray disposed centrally within the body defining at least a pair of elongated coin compartments communicating with the slots, a coin guard for the slots permanently secured to the tray including flexible locking legs for engaging the body to hold the tray in the body against unauthorized removal, and means insertable through the coin slots for flexing the legs to permit removal of the tray from the body.

In testimony whereof I affix my signature.

BRIAN T. MORAN.
